UNITED STATES PATENT OFFICE.

JOHN LAYTON GUERRANT, OF FRESNO, CALIFORNIA.

AMPLIFIER FOR TELEPHONE RECEIVERS.

Application filed January 31, 1924. Serial No. 689,697.

To all whom it may concern:

Be it known that I, JOHN L. GUERRANT, a citizen of United States, residing at 835 University Ave., Fresno, in the county of Fresno and State of California, have invented certain new and useful Improvements in Amplifiers for Telephone Receivers, of which the following is a specification, reference being had therein to the accompanying drawing.

The present invention relates to amplifiers for telephone receivers, and aims to provide a simple and inexpensive device of that kind capable of receiving and holding a telephone receiver so as to amplify the sounds, the device being intended especially as a loud speaker for radio receiving sets.

Another object of the invention is the provision of such an amplifying device having provision for encasing or housing the telephone receiver and connecting a horn therewith, so that the sounds will be magnified with a soft, smooth tone, and without the sounds being metallic or harsh.

A further object is the provision of novel means for obtaining a tight connection between the horn and receiver, in order that the sounds are transmitted from the receiver through the horn with good effect.

With the foregoing and other objects in view, which will be apparent as the description proceeds, the invention resides in the construction and arrangement of parts as hereinafter described and claimed, it being understood that changes can be made within the scope of what is claimed, without departing from the spirit of the invention.

The invention is illustrated in the accompanying drawing, wherein the figure is a median section of the device, portions being shown in elevation.

The amplifier is intended for use with various telephone receivers, especially those of the single type. The receiver 7 shown includes a case having the dished or concaved side or cap 8 formed centrally with the perforations or apertures 9 through which the sound waves pass from the enclosed diaphragm, and 10 indicates the wires or conductors to which the receiver is connected as usual.

In carrying out the invention, there is provided a case or box 11 of wood, rubber, fibre or other suitable material, which has the chamber 12, and a plug or cap 13 is screw-threaded into the mouth of the case

11 to close the chamber 12, and said cap or closure has the flange 14 in order that the case and cap can be screwed together conveniently by hand. The cap can be of any suitable material, the same as the case 11, and a cushion 15 of rubber, felt or other resilient material is disposed on the inner surface of the cap 13 to support the receiver 7 in the case with a cushioning action.

The case 11 is provided with a screw-threaded aperture or opening 16 opposite to the mouth of the case and cap 13, into which is screw-threaded the neck 17 of the horn 18. The neck 17 has a shank 19 projecting from the case 11 for convenience in screwing said neck into and out of the case, and the horn 18 may be of paper, wood, fibre, metal or other suitable material. The horn may be curved, as shown in full lines in the drawing, or may be of any other desired form.

A tubular throat member 20 of rubber, felt or other cushioning material is fitted in the neck 17 of the horn, and has an annular bead or gasket 21 at its inner end abutting the inner end of the neck 17 and adapted to abut the receiver 7 around the apertures 9, when the neck 17 is screwed into the case 11. The opening 22 of the throat member 20 is preferably restricted between the ends of said member and increases in diameter to the ends of said member, and the member 20 being of cushioning material will soften the sounds and avoid raspy noises such as produced by hard objects having vibratory or rubbing contact with one another.

The rim of the case 11 has a slot 23 for receiving the wires or cord 10 of the receiver, when the receiver is inserted into the case, said slot 23 extending to the mouth of the case.

When the cap 13 is unscrewed from the case, the receiver can be readily placed in or removed from the case, and when placed in the case, the receiver will rest on the cushion 15 of the cap when the cap is screwed into the case. The neck 17 of the horn is then screwed into the case until the bead or gasket 21 is compressed tightly between the neck 17 and receiver around the apertures 9, and the pressure will also compress the cushion 15 between the receiver and cap, whereby the receiver is cushioned from opposite sides. The bead 21 surrounding the apertures 9 will compel the sound waves to pass through the throat member 20 into and through the horn 18, and the sounds are

thus amplified with a clear tone of increased volume.

The device is capable of inexpensive manufacture, the case 11, cap 13 and neck 17 being readily turned from wood otherwise cheaply manufactured, and any suitable horn can be used. The present device also enables the receiver to be used in the usual way by placing it against the ear, 10 inasmuch as the receiver can be quickly removed by simply unscrewing the cap 13 from the case 11.

Having thus described the invention, what is claimed as new is:—

- 15 1. An amplifier comprising a case, a telephone receiver therein including a case having a sound aperture, a horn connected with the first named case in registration with said aperture, a resilient gasket between said 20 horn and second named case and surrounding said aperture, the first named case having a portion opposite to the horn against which the second-named case seats, and said portion and horn being adjustable relatively 25 to one another for clamping the second named case between said gasket and portion.
- 20 2. An amplifier comprising a case for enclosing a telephone receiver and having a portion against which said receiver is seatable, a horn having a neck screw-threaded into the case opposite to said portion, and a gasket carried by said neck beyond the inner 30 end thereof to contact with the receiver, with the receiver clamped between said gasket and portion.

3. An amplifier comprising a case for enclosing a telephone receiver, a horn having a neck engaging the case, and a resilient gasket beyond the inner end of the neck arranged to contact with the receiver and to be compressed between said neck and receiver, the case having adjustable means opposite to said gasket for clamping the receiver between said gasket and means. 40

4. An amplifier comprising a case for enclosing a telephone receiver, a screw cap for the case, a horn having a neck screw-threaded into the case opposite to said cap, and a gasket carried by the inner end portion of said neck to contact with said receiver, with the receiver clamped between said gasket and cap. 45

5. An amplifier comprising a case for enclosing a telephone receiver, a detachable cap for the case, a cushion carried by said cap to contact with the receiver, a horn having its neck engaged to the case opposite to said cap, and cushioning means to be disposed between said horn and receiver. 50

6. An amplifier comprising a case for enclosing a telephone receiver, a screw cap for the case, a cushion carried by said cap to contact with the receiver, a horn having a neck engaging the case opposite to said cap, and a gasket carried by said neck to contact with the receiver. 55

In testimony whereof I hereunto affix my signature.

JOHN LAYTON GUERRANT.
